UNITED STATES PATENT OFFICE.

LAWRENCE T. CHELLIS, OF CORVALLIS, OREGON.

SLEEVE-PRESSING FORM.

Application filed February 23, 1924. Serial No. 694,646.

This invention relates to pressing devices for apparel, and more particularly to a device for pressing sleeves.

One of the objects of this invention is to provide a form for pressing sleeves which is constructed and arranged so that the sleeves will be pressed without the usual creases along the sides.

Another object of the invention resides in providing a pressing form comprising two elongated ribs which are curved to conform to the natural curvature of the sleeve, and which are capable of being collapsed so as to permit their insertion in the sleeve, together with spring means for pressing said ribs outwardly when once in said sleeves, the spring means and ribs being constructed and arranged so that the ribs can be folded into closed position and occupy a minimum of space.

Still another object of this invention resides in the provision of a special type of spring for normally extending the ribs, which spring is peculiarly adaptable to provide a rugged extending means for the ribs, and yet permit the ribs to be folded to a compact closed position.

Yet another object of the invention resides in the peculiar conformation of the ribs whereby they will eliminate the usual creases formed in the sleeves during pressing.

These and other objects of the invention will be apparent from a perusal of the following specification when taken in connection with the accompanying drawing, wherein—

Figure 1 is a plan view of the pressing device with the end of the rib shown in section;

Fig. 2 is a longitudinal section on line 2—2 of Fig. 1;

Fig. 3 is a detail section on line 3—3 of Fig. 1;

Fig. 4 is a detail section on line 4—4 of Fig. 1.

Referring more particularly to the drawings in detail, the preferred form comprises two narrow elongated rib members 15, 16 of hard wood, or if desired, of spring steel. If the spring steel be used, it should be covered with cotton cord or cloth in order to prevent burning of the hands of the operator when using, inasmuch as the steel will be highly heated from the steam used in pressing. As shown clearly in Fig. 4, the exterior faces 2 of these ribs are curved to

provide a rounded outside face for the rib. The ribs are provided with means for normally expanding them, which in the present instance comprises two flat strips 17 and 18 adapted to lie between the ribs 15 and 16. These strips are each provided at their outer ends with two outwardly curved leaf springs 19, 20, 21 and 22. These pairs of strips 19, 20, 21 and 22 respectively, are riveted as at 23 and 24 to the opposite ends of the flat strips 17 and 18, so as to form springs of V-shaped construction, the apex of the V being at a point where the leaves are riveted to the flat springs. The outer end of each of these leaf springs 19, 20, 21 and 22 is curved and is looped around pivotal points 26, 27, 28 and 29 fastened in the outer ends of the ribs 15 and 16, the ribs being provided with cut-out notches 30, 31, 32 and 33 for this purpose. The inner ends of the strips 17 and 18 are connected together by means of a slot and rivet construction which while permanently connecting them together, permits of a relative sliding movement therebetween. In this construction, the strip 17 is provided with an elongated slot 34, while the inner end of the strip 18 is provided with two lugs 35 and 36 suitably riveted thereto, which lugs pass through the slots 34 and are headed so as to prevent their disengagement. When the ribs 15 and 16 are close together, the lugs 35 and 36 will slide to one end of the slot 34, and on the reverse or outward movement of the ribs 15 and 16 under the expanding pressure of the springs 19, 20, 21 and 22, these lugs will slide to the opposite end of the slot 34, and at such position will prevent any further expanding movement of the ribs 15 and 16. In this manner, the necessity for the flexible cords 11 and 12 is removed.

By means of the specific construction, it will be readily apparent that the pressing form possesses many advantageous features, first, the strips are of narrow curved formation and thereby readily lend themselves to easy insertion within the sleeve, and when once inserted, are of the correct conformation of the sleeve for pressing. Secondly, by reason of the curved outer surfaces 2 of the pressing ribs, when once inserted in the sleeve, there will be no sharp corners to permit crease marks to be formed on the sleeves. In addition to the curved surfaces, special attention is called to the relatively deep dimension 13 as indicated by the dotted

arrow in Fig. 4. This dimension 13 maintains the normal substantially oval or round conformation of the sleeve when in the form and between the steam pressing boards, so that it is not pressed out flat and creased. Furthermore, it is obvious that the peculiar type of spring used, together with the means for anchoring it to the ribs, provides a most ingenious means for enabling the ribs to be folded compactly together, while at the same time, assuring a construction wherein the springs will provide adequate pressure outward during the pressing operation.

It will be understood, of course, that in use the device is collapsed, is then inserted in the sleeve so that the springs will normally expand it to the size of the sleeve, so that the lining and goods of the sleeve are held tight, ready for the steaming operation. The form with the sleeve thereon is then simply laid in the usual type of steam press or steam board, and the steam applied for pressing. After the sleeve has been pressed the device is closed and removed from the sleeve.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A device of the class described comprising two substantially narrow elongated ribs, each having a curvature corresponding to the natural curvature of the part of the garment to be pressed, a flat strip arranged therebetween, spring means connected respectively to the outer ends of said ribs, and means to fasten the inner ends of said spring means together and to said strip.

2. A device of the class described comprising two substantially narrow elongated ribs each having a curvature corresponding to the natural curvature of the part of the garment to be pressed, a flat strip arranged therebetween, and spring means fastened to said strip and to the ends of said ribs and adapted to maintain said strip in substantial parallelism with and midway between said ribs and to force said ribs away from said strip.

3. A device of the class described comprising two substantially narrow, elongated ribs each having a curvature corresponding to the natural curvature of the sleeve to be pressed, two flat strips arranged therebetween with their inner ends overlapped, spring means connecting the outer ends of said strips to each rib to normally force said ribs outwardly, and a permanent connection between said overlapping ends of said strips constructed and arranged to permit said strips to slide longitudinally the one over the other, said connection being further arranged to limit such sliding movement in one direction.

4. A device of the class described comprising two substantially narrow, elongated ribs each having a curvature corresponding to the natural curvature of the sleeve to be pressed, two strips disposed therebetween with their inner ends overlapping, one of said strips having a longitudinal slot therein and the other of said strips having a desirable number of studs projecting through said slot, the outer end of each of said strips having V-shaped springs riveted thereto, the apex of said V-shaped springs being located at the point of riveting, the legs of said V being outwardly bowed and pivotally connected to the outer ends of said ribs.

5. A sleeve stretching device comprising spaced curved bars, curved springs hingedly connected to the bars adjacent the ends thereof, said curved springs extending towards each other and having their ends anchored together, a connecting rod connecting said last-named ends of the springs and means whereby the length of said connecting rod may be varied.

6. A sleeve stretcher comprising spaced bars, inwardly extending curved springs hingedly connected to the inner sides of the bars adjacent their ends, members connected to the inner ends of the curved springs and extending towards each other and an adjustable connection connecting the members extending towards each other together and forming means whereby said inwardly curved springs may be adjusted in relation to each other for varying the curvature of said curved springs.

In testimony whereof, I affix my signature.
LAWRENCE T. CHELLIS.
